UNITED STATES PATENT OFFICE.

BLOOMFIELD BROWER, OF NEW YORK, N. Y.

DESIGN FOR AN INKSTAND.

Specification forming part of Design No. **6,879**, dated September 9, 1873; application filed August 5, 1873.
[Term of Patent 3½ years.]

To all whom it may concern:

Be it known that I, BLOOMFIELD BROWER, of the city of New York, in the State of New York, have invented a Design for Inkstand, of which the following is a specification:

The nature of my design is fully represented in the accompanying photographic illustration, to which reference is made.

A represents the inkstand, in shape a six-sided prism. The sides have each plain raised borders *a*, with raised arabesque ornaments *n* in the center, which said borders and ornaments are polished or ground smooth. From two adjoining edges brackets *B* *B* are made to project, having on their upper surfaces three or more corresponding indentations, *333*. The

sides of these brackets are similarly ornamented with arabesque figures, polished or smoothed. Into the top of the inkstand a glass or china vessel, *C*, is fitted, and opposite to the brackets *B* a cover, *D*, is hinged to the top of the inkstand *A*, and ornamented with similar arabesque figures.

What I claim as my invention is—

A design for an inkstand and pen-rack combined, shaped and ornamented substantially in the manner above described.

BLOOMFIELD BROWER.
